US0D1054972S

(12) **United States Design Patent** (10) **Patent No.:** **US D1,054,972 S**
(45) **Date of Patent:** **** Dec. 24, 2024**

(54) **ENERGY STORAGE POWER**

(71) Applicant: **ShenZhen YunJi New Energy Technology Co., Ltd**, Shenzhen (CN)

(72) Inventor: **Songlin Xiao**, Shenzhen (CN)

(73) Assignee: **ShenZhen YunJi New Energy Technology Co., Ltd**, Shenzhen (CN)

(**) Term: **15 Years**

(21) Appl. No.: **29/857,942**

(22) Filed: **Oct. 26, 2022**

(30) **Foreign Application Priority Data**

Sep. 29, 2022 (CN) 202230648023.9

(57) **CLAIM**

The ornamental design for an energy storage power, as shown and described.

DESCRIPTION

FIG. 1 is a front perspective view of an energy storage power, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its usage status diagram;

FIG. 10 is a partial enlargement of FIG. 1; and,

FIG. 11 is a partial enlargement of FIG. 1.

The broken lines in the drawings illustrate the portions of the energy storage power, which form no part of the claimed design.

1 Claim, 11 Drawing Sheets
